(57) CLAIM

The ornamental design for a wrap, as shown and described.

DESCRIPTION

FIG. 1 is a front perspective view of a wrap showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depicted in FIG. 1 represent the outline of a person inserting their hands and arms through said wrap and not considered part of the invention as claimed.
